United States Patent Office

Des. 186,069
Patented Sept. 8, 1959

186,069

BUILDING PANEL

Kibbey W. Couse, Newark, N.J.

Application June 4, 1956, Serial No. 41,753

Term of patent 3½ years

(Cl. D18—2)

Figure 1 is a face view of a building panel embodying my new design, the reverse face being identical;

Figure 2 is a top edge view thereof;

Figure 3 is an edge view taken from the left of Figure 1;

Figure 4 is a bottom edge view of Figure 1, and

Figure 5 is a fragmentary cross sectional view taken on line 5—5 of Figure 1.

I claim:

The ornamental design for a building panel, as shown and described.
